UNITED STATES PATENT OFFICE.

EDGAR M. WILSON, OF DAVENPORT, IOWA.

BED CANOPY.

Application filed May 12, 1922. Serial No. 560,395.

To all whom it may concern:

Be it known that EDGAR M. WILSON, a citizen of the United States of America, residing at Davenport, in the county of Scott and State of Iowa, has invented new and useful Improvements in Bed Canopies, of which the following is a specification.

The object of the invention is to provide a removable and adjustable bed canopy for use primarily in connection with invalid or hospital beds as a means of protection against flies, mosquitoes and other insects, and especially to provide a structure of the type and for the purpose indicated whereby access to any desired portion of the enclosure may be afforded without the displacement or removal of adjacent portions of the screen and whereby the entire structure when not required may be folded into compact form for storage or transportation; and with these objects in view the invention consists in a construction and combination of parts of which a preferred embodiment is shown in the accompanying drawings, wherein:—

Figure 1 is a side view of a canopy embodying the invention applied in the operative position to a bedstead.

Figure 2 is a plan view of the same.

Figure 3 is a longitudinal sectional view taken through one end of the structure.

Figure 4 is a detail transverse sectional view taken through one side of the structure.

Figure 5 is a detail view of the ridge pole or longitudinal support.

Figures 6 and 7 are detail views respectively of the longitudinal side and end supporting bars detached.

The device is constructed as a unit separate from and optionally applicable to a bedstead of conventional form having the head and foot boards 10 and 11 and the side bars 12 connecting the same, and embodies primarily head and foot transverse supporting bars 13 and longitudinal side bars 14 terminally supported by the end bars and detachable therefrom, and a longitudinal series of transverse canopy sections each comprising a plurality of foldably (preferably hingedly) connected screen elements 15 adapted to form top and side walls for transversely arching the bedstead or the mattress supported thereby, with the free ends of the sections seated respectively upon the side bars 14.

In the illustrated embodiment of the invention the end bars 13 are provided with terminal stirrups 16 each provided with reversely disposed seats 17 and 18 for respectively engaging the side rails of the bedstead frame and receiving the side bars of the canopy frame, and both end and side bars 13 and 14 are provided in their upper sides with grooves or channels 13^a and 14^a for the reception of the adjacent lower edges of the screen elements, so that an efficient joint may be formed therebetween. The head and foot walls 19 of the canopy are represented by foldably connected screen sections 19^a and 19^b, hingedly connected at 19^c for folding into parallel relation when detached and serving as the terminal supports for the ridge pole 20 which is provided with terminal clips 21 to engage over the upper edges of said head and foot walls. Each transverse series of screen elements, consisting of a suitable frame 15^a and a filler of wire cloth 15^b or the equivalent thereof, is hingedly connected as at 15^c with the adjoining element of the series, with two of said elements forming the top and two forming the side walls of the structure so as to provide for folding into relatively compact form, while the several transverse series of screen elements are connected together to provide against longitudinal displacement by fastening means such as hooks 21^a engaging staples 22, and correspondingly the free edges of the terminal transverse series are connected by corresponding fastening devices 23 with the end walls 19, so that while the terminal or any desired number of elements or units of each transverse series may be displaced to give access to that portion of the interior of the structure as may be required, the engagement of the fastening means provides for holding the several elements or units in compact relation to constitute an unbroken protection for the occupant of the structure.

The side and end bars also preferably carry inwardly extended screen flaps 24 and 25 which project under the mattress (not shown) to cover the interval between the edges of the mattress and the said bars to prevent access of insects therethrough, and the side bars are preferably jointed as indicated at 26 at an intermediate point to permit of folding into relatively compact form.

105

110

Having described the invention, what is claimed as new and useful is:—

1. A canopy structure for bedsteads having transverse end and longitudinal side bars for support by the side rails of the bedstead, transverse series of foldably connected screen elements or sections transversely spanning the interval between the side bars and respectively forming portions of the top and side walls of an enclosure, 10 of the top and side walls of an enclosure, 10 end walls extending from said end bars to close the ends of the space defined by said transverse series of screen elements or sections and detachable fastening means for securing the adjacent edges of said series of screen sections together and for securing the terminal edges of the series to the end walls, the upper sides of said end and side bars being grooved or channeled to receive and seat the lower edges of the screen elements or sections forming the side and end walls. 55
2. A canopy structure for bedsteads having transverse end and longitudinal side bars for support by the side rails of the bedstead, transverse series of foldably connected screen elements or sections transversely spanning the interval between the side bars and respectively forming portions of the top and side walls of an enclosure, 60 end walls extending from said end bars to close the ends of the space defined by said transverse series of screen elements or sections and detachable fastening means for securing the adjacent edges of said series of screen sections together and for securing the terminal edges of the series to the end walls, a longitudinal ridge pole being extended between said end walls and having terminal clips for detachable engagement therewith. 70
3. A canopy structure for bedsteads having transverse end and longitudinal side bars for support by the side rails of the bedstead, transverse series of foldably connected screen elements or sections transversely spanning the interval between the side bars and respectively forming portions of the top and side walls of an enclosure, 75 end walls extending from said end bars to close the ends of the space defined by said transverse series of screen elements or sections and detachable fastening means for securing the adjacent edges of said series of screen sections together and for securing the terminal edges of the series to the end walls, the said end bars being provided with terminal stirrups having oppositely facing seats for respectively connecting the side rails of the bedstead and receiving the extremities of the side bars. 80
4. A canopy structure for bedsteads having transverse end and longitudinal side bars for support by the side rails of the bedstead, transverse series of foldably connected screen elements or sections transversely spanning the interval between the side bars and respectively forming portions of the top and side walls of an enclosure, 85 end walls extending from said end bars to close the ends of the space defined by said transverse series of screen elements or sections and detachable fastening means for securing the adjacent edges of said series of screen sections together and for securing the terminal edges of the series to the end walls, the side and end bars being provided with inwardly directed screen flaps for extension at their edges under the mattress of the top and side walls of an enclosure, 90 supported by the bedstead. 95
5. A canopy structure for bedsteads having transverse end and longitudinal side bars for support by the side rails of the bedstead, transverse series of foldably connected screen elements or sections transversely spanning the interval between the side bars and respectively forming portions of the top and side walls of an enclosure, 90 end walls extending from said end bars to close the ends of the space defined by said transverse series of screen elements or sections and detachable fastening means for securing the adjacent edges of said series of screen sections together and for securing the terminal edges of the series to the end walls, the side and end bars being provided with inwardly directed screen flaps for extension at their edges under the mattress of the top and side walls of an enclosure, 95 supported by the bedstead. In testimony whereof he affixes his signature.

EDGAR M. WILSON.
